UNITED STATES PATENT OFFICE.

CALVIN G. UDELL, OF NORTH INDIANAPOLIS, INDIANA.

COAT-RACK.

SPECIFICATION forming part of Letters Patent No. 372,502, dated November 1, 1887.

Application filed May 10, 1887. Serial No. 237,786. (No model.)

To all whom it may concern:

Be it known that I, CALVIN G. UDELL, of North Indianapolis, county of Marion, and State of Indiana, have invented certain new and 5 useful Improvements in Coat-Racks; and I do hereby declare that the following is a full, clear, and exact description thereof, reference being had to the accompanying drawings, in which like letters refer to like parts.

10 My invention consists in an improved construction of coat-racks, and will be understood from the following description.

In the drawings, Figure 1 represents a front view of my device, the middle hook being removed. Fig. 2 represents a side view of one of the hooks, showing the method of attachment to the wooden strip or board. Fig. 3 is 15 a rear view of the hook. Fig. 4 is a detail view of the upper lug, *l*, and its notch *n*, 20 through which the pin *p* passes.

My device is constructed as follows: The brackets are made, in the form shown in Fig. 2, of malleable iron, and have three hooks, 25 an upper one, *h*, an intermediate one, *h'*, which is next in length, and a lower and shorter one, *h*². The back is provided with two lugs, the upper one, *l*, having a notch, *n*, to admit the passage of the pin *p*. The lower lug, *l'*, is made solid.

30 *s* is a strip of wood about forty inches in length, three inches in width, and from three-eighths to half an inch in thickness, in which holes *o* are bored in pairs, one above another, at a distance of eight inches apart. In the 35 upper edge of this strip holes are bored to admit the pins *p*. The holes *o* of the strip are made of sufficient size to receive the lugs *l* *l'* of the brackets, and when these are inserted the pins *p* are driven in the holes made in the edge 40 of the strip, so that each pin will pass through

the notch *n* of the upper lug, *l*, thus securing it firmly to the strip, and these pins may be easily drawn by a knife, when desired, the brackets removed from the strips, and the whole device packed up in convenient form 45 for shipment. The brackets being fastened to the strip, ordinary wire eyes, *e*, are screwed into the edge of the strip for hanging the device upon the wall.

My invention therefore consists, first, in the 50 form of the rack having three hooks of different lengths, one above the other, and secured to a strip; second, in the peculiar method herein shown of fastening the brackets to the wooden strip or back, and, third, in the combination of the several parts, as hereinbefore 55 described.

What I claim as my invention, and desire to secure by Letters Patent, is the following:

1. A bracket comprising two or more hooks, 60 one above the other, provided with lugs upon the back for entering holes in the back strip, the upper one of which is notched to admit the passage of the pin for securing the device to such back strip, in combination with such back strip, the pin *p* for connecting the parts, and means for suspending the same, substantially as shown and described.

2. A bracket for clothes-racks, comprising the hooks *h* *h'* *h*², with upper lug, *l*, having a 70 notch, and lower lug, *l'*, the back strip, *s*, having openings to receive the lugs, the pin for uniting the parts, with eyes *e* for suspending the same, substantially as described.

In witness whereof I have hereunto set my 75 hand this 6th day of May, 1887.

CALVIN G. UDELL.
